SAFETY LOCK FOR GAS COCKS

Maximilian P. Janisch, Milwaukee, Wis., assignor
to Autogas Corporation, Chicago, Ill., a corpo-
ration of Delaware

Application December 21, 1931, Serial No. 582,278
Renewed December 22, 1937

8 Claims. (Cl. 158—115)

The primary object of the present invention is the provision of means which will act as a safety device in obviating the liability to the occurrence of an explosion of the gas accumulated in the oven of a kitchen range, when the pilot light with which the oven is equipped, has become extinguished from any cause.

In gas consumers of the character indicated, the pilot light for the oven is concealed from casual view, and it cannot be determined by mere routine inspection whether or not such light is burning. In most instances, the pilot light burns continuously, as it is intended to do. But in other instances, it has become extinguished from any one or more of several causes, and when this condition arises, it is without the knowledge of the housewife or domestic.

When it is desired to make use of the oven, the housewife or domestic turns on the supply of gas. If the pilot light in the oven be burning, the oven burners will be ignited within one or two seconds of time, which result is made known by an audible "pop" in the ignition of the gas when it starts to flow through the burners, as well as by a visible illumination. In the event that the pilot light has become extinguished, there will be no such audible or visual indications, and the first impulse of the housewife or domestic, and more frequently the latter, is to attempt to ignite the gas at the oven burners by seeking to apply a lighted match thereto. Meanwhile, the oven has become filled with the highly inflammable and explosive gas, and when the lighted match is inserted in the oven, an explosion occurs. Very often the latter is attended by the infliction of serious damage to both person and property.

The present invention has for its purpose the provision of means for eliminating the occurrence of accidents of this nature, and this result is effected by arranging a thermostatic element in such proximity to the pilot light in the oven of a kitchen range, that such element exerts an actual control over the supply of gas. The action of the thermostatic element is to lock the gas cock, so that the latter cannot be opened until after the pilot light has been relighted.

A clearly displayed and readily discernible signal of mechanical form, also operated by the action of the thermostatic element, may be employed to indicate to the eye the lighted or unlighted condition of the pilot light in the oven. The said signal provides an additional safeguard against accident, and may be used in connection with the oven gas cock lock, or independently of the same in ranges not equipped with such a

lock. The lighting pilot, for igniting the oven burners, may be used independently of both the gas cock lock and the signal.

The embodiment of the invention in the one form illustrated, together with its operation, will now be described, and the novelty thereof will be pointed out in the appended claims.

The drawing herewith shows in perspective a fragmentary view of a gas-burning kitchen range, the oven of which is provided with a pilot light, and showing also my safety device and signal as associated therewith, together with the connections which control the supply of gas.

In the drawing, the numeral 10 indicates the grid of a gas burning kitchen range, and the numeral 11 a part of the oven structure associated therewith. The oven may be of any usual or suitable construction, forming a closure and provided with doors, one of the latter of which is indicated by the numeral 12.

The gas manifold 13 is connected to a source of supply in the usual manner. Gas burners 14, in plural numbers, one of which is shown, are associated with the grid, and are each supplied with gas by a feeding pipe 15, connected in the usual manner with the manifold 13, through the mixing bell. A stop cock 16 controls the flow of gas from the manifold to the feeding pipe 15, and to the burner 14.

A feeding pipe 17, connected to the manifold 13 in the manner before described, is adapted to supply gas to the burners 18, 18, arranged within the closure of the oven 11. A stop cock 19 controls the flow of gas from the manifold to the feeding pipe 17, and to the oven burners.

A by-pass in the form of a small tube 20, is connected at one end to the stop cock 19, so as to divert the flow of a small quantity of gas from the feeding pipe 17 when the valve of the stop cock 19 is opened. The by-pass 20 is extended through one wall of the oven, and may be supported in a stationary position by means of a bracket 21, attached to the wall of the oven. The by-pass is then extended a short distance beyond or away from the wall of the oven, and is provided at its free end with a housing 22, formed as a short hollow cylinder. The housing 22 is conveniently supported upon the by-pass 20, by entering the free end of the latter in an opening in the wall of the housing, which permits the said housing to be slipped over the free end of the by-pass, and secured thereon. An outlet within the housing immediately adjacent the pilot, is thus provided for the small quantity of gas diverted through the by-pass 20, to

- form the igniting jet for the oven burners. The opposite side of the housing in advance of the end of the by-pass, is cut away to permit the jet to spurt to the nearest oven burner.
- 5 A small bore tube 23, leading from the manifold 13, through one wall of the oven, is extended at its other end through an opening in one side of the housing 22, so as to discharge at all times within the housing a small quantity of gas, the purpose of which, when ignited, is to form a constantly burning pilot light. The pilot light is intended to burn continuously, but sometimes it will become extinguished. The arrangement of the pilot light in the oven is such that ordinarily it is not within the vision of a person using the range.
- When the valve of the gas cock 19 is operated to permit the flow of gas through the feeding pipe 17 to the oven burners 18, 18, the small stream or jet of gas, diverted through the by-pass 20, will become ignited by the pilot light, and the gas flowing at the same time from the plurality of burners 18, will be ignited by the said jet. In practice, the oven burners 18, 18, are arranged a slight distance apart so that the burners beyond the one in proximity to the pilot light and the lighting jet, will be quickly lighted in succession, until all of the burners of the series have been ignited.
- 30 In the opening part of this specification, I have outlined my invention as residing in the provision of safety means which will obviate the liability to explosions, which follow attempts to ignite the oven burners by applying a match there-to, when the same fail to be ignited by the pilot light. I achieve this result by attaching to the housing 22 of the pilot light, as to an ear 24 thereon, one end of a strip 25, of thermostatic metal. The secured end of the strip 25 is imme-diately within the zone of heat generated by the burning pilot light. Unequal expansion of the laminae of the thermostatic strip 25 will cause the free end of the strip to rise above or fall below its normal plane, depending upon which 35 side of the strip is arranged over the flame of the pilot light. The full lines in the drawing show the normal position of the strip, and the dotted lines the position assumed by the free end of the strip, when heat is applied thereto.
- 40 This vibratory motion of the free end of the strip 25 is used to accomplish either or both of two purposes. A vertically disposed rod 26 of light material, is supported at its lower end upon the free end of the strip 25, or connected thereto, so as to have a longitudinal movement in correspondence with the movement of the strip 25. A bell-crank 27 is pivoted on the side of the oven. One end of the bell-crank is connected as at 28 to the rod 26, so as to partake of the movements 45 thereof. The other arm of the bell-crank is connected by a link 29 to a detent 30, pivotally mounted on a stud fixed at some convenient point to the structure.
- 45 The stem of the gas cock 19 is provided with a laterally extending pin 31, conveniently arranged at a 90° angle with relation to the key or handle 32. When the thermostatic strip 25 has been distorted by the heat applied thereto, and moved upwardly to its dotted line position, the detent 30 will be turned so that the swing-ing end thereof will stand clear of the path of movement of the radial pin 31. The valve of the stop cock 19 may then be opened, to permit 50 gas to flow to the burners 18, 18, of the oven, for as long a period of time as the latter may
- 5 be in use, and upon the conclusion of which the stop cock 19 will be closed, to shut off the flow of gas to the oven burners. If thereafter, from any cause, the pilot light in the oven should become extinguished, the reaction of the thermostatic strip 25 will reverse the position of the parts, and will move the swinging end of the detent 30 into the path of movement of the radial pin 31, and effectively lock the gas cock 19, against a movement which will open the valve to the 10 flow of gas.
- 55 The quantity of gas escaping through an un-lighted pilot is very small, and in view of the dis-sipation of the same in the atmosphere, there will be no accumulation in a volume sufficient to 15 cause an explosion. Hence, there is not pres-ent a liability to danger, if the pilot light be extinguished.
- 60 Upon discovering that the stop cock 19 is locked against any flow of gas, it will be necessary only to relight the pilot by applying a match there-to. In a few seconds the thermostatic strip 25 will respond to the heat, and the swinging end of the detent 30 will be withdrawn from its ob-structing position. The gas cock 19 may then be 20 operated to permit gas to flow to the burners of the oven.
- 65 As an aid in determining whether the pilot light is burning, I may provide a mechanical signal, and connect it so that it will be operated 25 to indicating position by the thermostatic element 25. A simple form of this arrangement will be the provision of a signal 33, pivoted in some form of housing on the side of the oven, and connected with the rod 26, so that in the longitudinal move-30 ments of the said rod, the signal will be dis-played while the pilot is burning, and withdrawn from view when it is not, or vice versa. The signal 33 is pivoted at 34, and provided with a radial arm 35, to which the upper end of the rod 40 35 is connected. The dotted lines show the signal as exposed at the time the thermostatic element 25 has been displaced from its normal plane by the heat of the pilot light. The full lines show the signal 33 as withdrawn from view, in the 45 reaction of the strip 25.
- 70 My thermostatically controlled safety device may also be used to lock the gas cocks 16 con-trolling the supply of gas to the several burners 14, by the simple expedient of arranging a ther-50 mostatic strip in proximity to the pilot light for the burners 14, and connecting the pivoted lock-ing detents 36 in series, so as to lock all of the gas cocks 16.
- 75 Where the safety device described cannot be 55 applied to the control of the gas cocks, I may omit the connections to the latter, and use the signal 33 to indicate the condition of the pilot light in the oven.
- 80 The arrangement of the by-pass 20 so as to dis-charge a jet of gas in proximity to the pilot light in the oven, insures a much quicker and more certain ignition of the oven burners, for the rea-son that the jet of gas flowing from the by-pass is projected toward the nearest oven burner 18, 65 and the flame is carried instantly from the pilot light to the gas flowing from the oven burners. A great advantage of this arrangement lies in the fact that the gas escaping into the oven from the plurality of burners 18, is ignited before the 70 free gas has an opportunity to accumulate in such volume as to constitute a menace.
- 85 The drawing is merely illustrative as a single application of my invention, which is also capa-

ble of use in connection with gas burners or lighters located outside of the oven, as well.

Having thus described my invention, what I claim and desire to secure by Letters Patent of the United States, is:

5. 1. In a gas range, an oven having a burner, means including a pilot burner and lighter for automatically igniting gas emitted from said first named burner, means including a manually actuated cock for controlling the supply of gas to said lighter and first named burner, a detent movable to lock said cock in closed position, and thermostatic means controlled by the heat of said pilot burner for controlling said detent to prevent opening of said cock when said pilot burner is extinguished.
10. 2. In a gas range, an oven having a burner, a manually actuated cock for controlling the supply of gas thereto, a pilot burner, means controlled by said cock and ignited by said pilot burner for automatically igniting said first named burner upon supplying gas to the latter, a detent movable to lock said cock against opening, and thermostatic means controlled by the heat of said 15. pilot burner for controlling said detent to prevent opening of said cock when said pilot burner is extinguished.
15. 3. In a gas range having a burner, means including a pilot burner and lighter within said oven normally effective to automatically ignite said first named burner whenever gas is supplied to the latter, a manually actuated cock for controlling the supply of gas to said lighter and said first named burner, a detent movable to lock said cock against opening, and thermostatic means controlled by the heat of said pilot burner for controlling said detent to prevent opening of said cock when said pilot burner is extinguished.
20. 4. A safety device for use on gas ranges comprising a main burner, a gas conduit for said burner, a valve in said conduit controlling the fuel supply to said burner, an ignition burner controlled by said valve and positioned to ignite the main burner, a pilot burner positioned to ignite the ignition burner, and a thermal lock mechanism subject to the heat of the pilot burn- 25.
- er and operable to lock said valve in closed position if the pilot burner should become extinguished while the valve is in closed position, and to permit opening the valve only if the pilot burner is burning.
5. In a gas burning device having a main burner, means including a pilot burner and an igniting burner for automatically igniting gas emitted from the main burner, thermostatic means responsive to the temperature of the pilot burner, 10 valve means for controlling the supply of gas to the main burner and igniting burner, and means controlled by the thermostatic means to prevent opening of the valve means when the pilot burner is extinguished and to permit opening of the 15. valve means only when the pilot burner is burning.
6. In a gas burning device having a main burner, means including a pilot burner and an igniting burner for automatically igniting gas emitted from the main burner, valve means for controlling the supply of fuel to the main burner and igniting burner, and means movable in response to the heat of the pilot burner and engageable with said valve means to prevent opening thereof when the pilot burner is extinguished.
7. In a gas burning device having a main burner, means including a pilot burner and an igniting burner for automatically igniting gas emitted from the main burner, valve means for controlling the supply of fuel to the main burner and igniting burner, thermostatic means movable in response to the heat of the pilot burner, and a member moved by said thermostatic means into engagement with the valve means to prevent opening thereof when the pilot burner is extinguished.
8. A safety device for a fluid fuel burner having a supply conduit with a control valve therein comprising a pilot burner connected to the supply conduit anterior to the valve, an igniting burner connected to the supply conduit posterior to the valve, and means responsive to the heat of the pilot burner to lock the valve against opening when the pilot burner is extinguished.

45. MAXIMILLIAN P. JANISCH.
